UNITED STATES PATENT OFFICE.

GEORGE LAYTON FRASER, OF HONOLULU, TERRITORY OF HAWAII, ASSIGNOR TO CALIFORNIA PACKING CORPORATION, OF SAN FRANCISCO, CALIFORNIA, A CORPORATION OF NEW YORK.

PINEAPPLE-SLICER.

1,266,447.

Specification of Letters Patent. Patented May 14, 1918.

Application filed February 12, 1918. Serial No. 216,706.

To all whom it may concern:

Be it known that I, GEORGE LAYTON FRASER, a citizen of the United States, residing at Honolulu, Territory of Hawaii, have invented certain new and useful Improvements in Pineapple-Slicers, of which the following is a specification.

My invention relates to the class of fruit slicing machines, and is particularly adapted 10 for the slicing of pineapples.

The object of my invention is to provide a simple machine for this purpose, capable of rapid and effective work, the slicing being accurate, with no waste, and the result 15 uniform and attractive in appearance.

To this end my invention consists in the novel slicing machine which I shall herein-after fully describe by reference to the accompanying drawings, in which—

20 Figure 1 is a front elevation of my machine.

Fig. 2 is a side elevation of the same partly in section, on the line 2—2 of Fig. 3.

Fig. 3 is a top-plan of the same, a portion 25 of the top frame plate and a portion of the top-carrier being broken away.

Fig. 4 is a section on the line 4—4 of Fig. 1.

1 is a frame having a top plate 2 and a 30 cross support 3, in which is journaled the carrier-shaft 4.

Upon the upper portion of this shaft is mounted the carrier which comprises a plurality of horizontally disposed members 5, 35 forming a tier, the members being secured together by bolts 6 and their hubs 7 resting on one another successively, and keyed to the shaft 4 for revolution therewith as indicated at 8 in Fig. 2.

40 The hubs 7 are sufficiently thick to provide for peripheral spaces 9 between said members. This construction is the preferred, though not necessarily the only form, it being essential merely that the carrier be provided with a vertical series of peripheral spaces for the reception of the knives as will presently appear. But by having the carrier composed of independent members secured together, the unit may be readily built up 45 and varied in size at will.

The uppermost member of the carrier is best formed as a plate, as seen in Fig. 3, but the remaining members are preferably formed as spiders, as shown in said figure.

55 Each member of the carrier unit has a plu-

rality of holes made in it, here shown, for example, as six, though this number may be varied as desired. These holes are aligned vertically throughout the tier of members, so that in the carrier there are six vertical 60 pockets 10, the upper end of each pocket being adapted, during the revolution of the carrier to successively register with a feed opening 11 in the top plate 2 of the frame, and with the overlying feed hopper 12, as 65 seen in Fig. 2, and the lower end of each pocket being terminated by a frame plate 13, in which at one side is a discharge opening 14 with which said pockets, during the revolution of the carrier, successively register, said opening 14 itself registering with the discharge chute 15.

Upon a revolving shaft 16 mounted in the frame 1 at one side, is a tier of spaced knives 17, in the form of disks, so disposed that 75 they enter and revolve within the interspaces 9 of the carrier unit, as seen in Figs. 1 and 3, and intersect the path of revolution of the carrier pockets 10.

Motion is imparted as follows:— 80

Power is led into the machine through a gear 18, and drive shaft 19. A bevel gear 20 on shaft 19 meshes with a bevel gear 21 on a vertical countershaft 22, which shaft carries a gear 23. The gear 23, carries a pin 85 24, comprised in a Geneva movement including the wheel 25 mounted on the carrier shaft 4, as seen in Fig. 4. Thus an intermittent or step by step revolution is imparted to the carrier unit, so that each of 90 its pockets 10 comes to rest temporarily under the feed hopper 12 and over the discharge chute 15.

The gear 23 of the countershaft 22 meshes with a gear 26 on a countershaft 27, and 95 this gear meshes with a pinion 28 on the knife shaft 16, as seen in Fig. 4, whereby a continuous rotary movement is imparted to the tier of knives 17.

The operation is as follows:— 100

The fruit is fed from the hopper 12 to each of the pockets 10, as said pocket comes to rest under the hopper, and as a given fruit is carried around by the revolution of the carrier to the sphere of action of the 105 knife tier 17, it is sliced horizontally; and when the sliced fruit reaches the discharge chute 15, it drops therein, the discharging pocket 10 being temporarily at rest there-over; while at the opposite side a receiving 110

pocket is temporarily at rest under the feed hopper 12.

The object in making the uppermost member of the carrier unit a disk, instead of a spider, is to prevent the fruit from catching between the arms of a spider-like disk, and clogging the machine. As it is, the fruit resting on the top disk is accurately moved, without injury, into its pocket.

I claim:—

1. A machine for the described purpose, comprising a carrier with a series of peripheral spaces, and with fruit-receiving pockets traversing said spaces; a series of spaced knives adapted to enter said spaces and intersect the carrier pockets; means for feeding the fruit to successive pockets; delivery means for receiving the sliced fruit from successive pockets; and means for imparting a step by step revoluble movement to the carrier to cause it to come to rest under the feeding means and over the delivery means.
2. A machine for the described purpose, comprising a revoluble carrier with a series of peripheral spaces, and with fruit-receiving pockets traversing said spaces; a revoluble series of spaced knives adapted to enter said spaces and intersect the path of revolution of the pockets; means for rotating said knife series; means for feeding the fruit to successive pockets; delivery

means for receiving the sliced fruit from successive pockets; and means for imparting a step by step revoluble movement to the carrier to cause it to come to rest under the feeding means and over the delivery means.

3. A machine for the described purpose, comprising a revoluble carrier with a series of peripheral spaces, and with fruit-receiving pockets traversing said spaces; a rotating series of spaced knives adapted to enter the carrier spaces and traverse the path of revolution of the carrier pockets; means for feeding the fruit to successive pockets; delivery means for receiving the sliced fruit from successive pockets; parallel shafts upon which the carrier and the knife series are respectively mounted; a power shaft, and a countershaft geared together; transmitting mechanism between the countershaft and the carrier shaft adapted to impart to the carrier shaft an intermittent movement to cause the carrier to come to rest under the feeding means and over the delivery means; and a gear train between said countershaft and the knife series shaft.

In testimony whereof I have signed my name to this specification in the presence of two subscribing witnesses.

GEORGE LAYTON FRASER.
